UNITED STATES PATENT OFFICE.

CLYDE E. COCHRAN, OF CLEVELAND, OHIO, ASSIGNEE TO THE ELWELL-PARKER ELECTRIC COMPANY OF AMERICA, OF CLEVELAND, OHIO, A CORPORATION OF WEST VIRGINIA.

CONTROLLER.

1,073,397.

Specification of Letters Patent. Patented Sept. 16, 1913.

Application filed July 22, 1912. Serial No. 710,793.

To all whom it may concern:

Be it known that I, CLYDE E. COCHRAN, a citizen of the United States, residing at Cleveland, in the county of Cuyahoga and State of Ohio, have invented a certain new and useful Improvement in Controllers, of which the following is a full, clear, and exact description, reference being had to the accompanying drawings.

10 This invention relates to electric controllers preferably for use on moving structures, as motor vehicles, electric cars, traveling cranes, elevators and the like.

15 The object of the invention is to provide a safety device rendering the controller operable only when the attendant is in his normal or operating position, the circuit being automatically broken if the attendant leaves that position, and the controller not 20 being again operable until he returns.

More specifically, the invention includes the combination with a vehicle, of an electric controller thereon and a platform for supporting the attendant, and mechanism 25 connecting the platform with the controller so that the controller may only be operated when the attendant is on the platform. When the attendant leaves the platform a supplemental switch is automatically 30 opened, breaking the circuit, whether the controller lever be in the "off" position or otherwise. If it is not in the "off" position it must be returned to that position before the supplemental switch can be closed.

35 The invention comprises the means by which I carry out the above operations, as hereinafter more fully explained and as definitely set out in the claims.

In the drawings, Figure 1 is a front elevation of my controller with the cover removed; Fig. 2 is an end view thereof, the end plate of the controller casing being removed and the controller being coupled with the platform and safety mechanism; Fig. 3 40 is a side elevation on a reduced scale of a portion of a motor truck equipped with my controller and safety mechanism; Fig. 4 is a detail showing an end view of the safety locking device on the controller shaft; Fig. 5 45 is an enlarged sectional side elevation of a portion of the controller; Fig. 6 is a plan, partly sectional and partly broken away, of the controller.

As shown in the drawings, 10 represents

the casing of the controller, in which is 55 mounted the controller barrel 11 having contact plates, and the cooperating contact fingers 12. The controller barrel is on a shaft 13 which is journaled in bearings 14 at one end of the casing, and a bearing within the 60 casing provided by the frame bracket 15 and cap 16. On the shaft is a pinion 17, which meshes with an operating segment 18 on the operating shaft 19. This shaft extends 65 through the casing and is provided with any suitable means for rocking it and thereby operating the controller. The operating means may be attached to the shaft at either end of the casing, or there may be two operating means, one at each end, as desired. 70 The controller barrel is provided with a usual notched indicator wheel 20 with which coacts a roller 21 on an arm 22, spring pressed against the indicator wheel.

The parts so far described may be of any 75 suitable construction. I have found the embodiment shown in the drawings to be a satisfactory one. It is to be understood that, when the main shaft 19 is turned in one direction the circuit is connected to accelerate the motor to drive forwardly the vehicle or other connected structure, while the turning in the opposite direction will reverse the motor and drive the vehicle backward.

To make the operation of the controller dependent on the attendant being in proper position, I provide the following mechanism: On the bearing bracket 15 is a suitable stationary upright guideway provided 80 by the blocks 30 in which are parallel grooves facing each other, in which grooves lie guiding ribs 32 of a vertical cross head 31. This cross head is an open structure having a pair of separated vertical plates 95 carrying the ribs mentioned and connected together at their lower ends, and at that point the cross head carries a contact brush 33, which normally engages stationary terminals 34. Pivoted in the cross head between its side plates near their upper ends, is a bell crank 36 which, at its lower end, carries a roller 37. This roller coacts with a cup 24 on the end of the barrel shaft 13 in a manner hereinafter described. The 100 horizontal arm of the bell crank 36 is connected by a pin and slot connection with a vertical rod 40 which is slidable in ears 38

of the cross head 31. On this rod 40 is a head 41 which has a sliding connection with a yoke 42, which itself slides on the rod 40. A compression spring 43 is interposed between the head 41 and the other end of the yoke. The yoke is connected with a depending rod 45. This rod 45 is connected by any suitable mechanism with a folding platform. As shown, the connection is by a 10 bell crank 46 connected with the rod 45, an adjustable link 47, 48, and an arm 49, which projects rigidly from the platform 50. A suitable spring placed anywhere in the mechanism, as indicated by the spring 52, 15 tends to move the mechanism in a direction to elevate the platform.

With the mechanism described, when the operator is standing on the platform 50, the parts are in the position shown in Figs. 20 2 and 3. Accordingly, the yoke 42 is drawn down, the cross head 31 is in its lowermost position and the brush 33 is contacting with the terminal 34. The spring 43 in the yoke 42 enables the platform to swing to 25 the limit of its movement after the engagement of the brush 33 with the terminal 34. In this position of the parts, the roller 37 is beneath the cup 24 on the controller shaft, and the controller is operated entirely independently of the safety mechanism described. The terminals 34 and 33 are inserted in series in one of the main leads to the controller, but when these parts are in contact, the controller turns on and off the 30 current in the usual manner. If, however, the operator should leave the platform 50, the safety mechanism controlled thereby at once operates and breaks the circuit. This is accomplished as follows: Suppose first 35 that, when the operator leaves the platform, the controller barrel is standing at "off" position. In that position, a notch 25 through the wall of the cup 24 stands directly over the roller 37. Now, when the 40 platform 50 is relieved of the operator's weight, the spring 52 acts to swing the platform upwardly and to raise the rod 40, and the rod, shoving upwardly on the spring 39, raises the cross head 31, which carries 45 the roller 37 into the interior of the cup 24 through the notch 25, the terminal 33 moving upwardly away from the terminal 34. Thus the circuit is automatically opened when the operator leaves his platform. 50 Now the circuit being open at the terminals 33, 34, it is immaterial if any one, tampering with the mechanism, should turn the controller to an active position. By such movement, the cup is turned around so 55 that its wall lies beneath the roller 37, thereby holding the cross head 31 elevated and retaining the contact open at the terminals 33, 34. It is impossible to close the 60 terminals 33, 34 until the controller barrel 65 has been brought to the "off" position, thus

bringing the notch 25 beneath the roller 37 and allowing it to pass through that notch and the cross head to descend. Accordingly, stepping on the platform when the controller is at active position would simply result in compressing the spring 43, and the safety terminals would still be maintained apart, the roller 37 being held elevated by the wall of the cup beneath it.

Means are provided for automatically returning the controller barrel to the "off" position when the operator takes his hand off of the controlling lever, as for example the opposed springs 55 and 56 (Fig. 3) which engage the rock arm 57 on the main shaft 19, this arm being shown as connected by a link 58 with the handle 59. But suppose that, when the operator leaves the platform, the controller lever is jammed or the barrel for any reason is in an active 70 position instead of an off position, as it should be. Under these circumstances, the notch 25 will not be directly above the roller 37, so that the operation will be somewhat different. Namely, on the first upward movement of the rod 40 the cross head 31 can not rise because it is blocked by the roller 37 engaging the outside of the cup 24. The slot 54 in the head of the rod, however, allows the rod to rise, and, after 75 the movement provided by this slot (the spring 39 compressing during this action) the lower end of the slot engages the pin on the bell crank 36 and a continued movement rocks the bell crank, withdrawing the 80 roller 37 from beneath the cup 24. Thereupon, the cross head suddenly rises, the roller 37 snapping across the wall of the cup, abruptly breaking the contact at the 85 terminals, 33, 34. In this movement, the 90 end of the roller 37, having passed across the arcual wall of the cup 24, stands opposite the cup entrance. Now, on any downward movement of the platform, under 95 these conditions, the roller swings into the 100 cup, with the wall of the cup extending below the roller. It is accordingly, impossible to close the terminals 33 and 34 until the controller shaft has been turned to 105 bring the barrel into "off" position, which 110 causes the notch 25 to come below the roller and free the cross head.

From the above description, it will be seen that, when the operator leaves the platform, whether the controller is on or off, the 115 safety contact is immediately broken, and it is impossible to close it again unless the controller be at off position. Accordingly, my mechanism protects against accident from the operator leaving his post when the current 120 is on or from any one tampering with the device while the operator is off the platform.

I have found the safety mechanism described to be of great advantage, and especially useful, for example, in baggage trunks. 130

Such a baggage truck is illustrated in Fig. 3, where 60 indicates the general floor or platform of the truck and 61 the wheels. The platform on which the operator stands is shown at 50 and a lever for operating the controller at 59. Of course, this is simply one adaptation or embodiment of my device, and I do not intend to limit myself thereto.

Having thus described my invention, what I claim is:

- 10 1. The combination, with a controller, a movable safety member, separable terminals for controlling the circuit of the controller, means for separating such terminals when the safety member is moved, whether the controller be at "off" or "on" position, means for preventing the return of the terminals unless the controller be in the "off" position, a movable platform, and a connection between it and the safety member.
- 15 2. The combination, with a controller, a movable support, a spring tending to raise the support, separable terminals for controlling the circuit to the controller, means for separating such terminals when the support is raised, and means for preventing the return of the terminals unless the controller be in the "off" position.
- 20 3. The combination, with a controller barrel and means for operating it, of separable terminals in the controller circuit, a movable support, connecting mechanism adapted to separate the terminals when the support is raised, and mechanism between the connecting mechanism and the controller barrel adapted to prevent the return of the terminals unless the controller be in "off" position.
- 25 4. The combination of a controller barrel, a cup movable therewith and having an opening through its wall, a device having a roller adapted to coact with the inside or outside of said wall and enter such opening, coöperating terminals, and mechanism for separating the same connected with said device, whereby the terminals may separate when the opening is opposite said device.
- 30 5. The combination of a controller barrel, a member movable therewith and having a notch, a device adapted to coact with said member and enter such notch, coöperating terminals, mechanism for separating the same connected with said device, whereby the terminals may separate when the notch is opposite the device, a movable support, and connecting mechanism between the same and said device.
- 35 6. The combination, with a controller barrel, of a cup rotatable therewith and having a notch through its wall, a roller adapted to stand either on the outside or the inside of the cup and adapted to pass through said notch and over the wall of the cup, a separable terminal controlled by the position of said roller, and means for moving the roller

from the outside to the inside of such cup over the wall of the cup.

7. The combination, with a controller barrel, of a member rotatable therewith having a notch, a roller coacting with the member, the notch being positioned to stand opposite the roller when the controller barrel is in the "off" position, means for moving the roller over the edge of the member when the controller barrel is in another position than the "off" position, and a separable terminal connected for movement with said roller.

8. The combination, with a controller barrel, of a cup on the end of the barrel shaft, said cup having a notch in its wall, a roller coacting with the wall of the cup, the notch being positioned to stand opposite the roller when the controller barrel is in another position than the "off" position, and a separable terminal connected for movement with said roller.

9. The combination, with a controller barrel, of a cup rotatable therewith and having a notched wall, a slide adjacent to the cup, a bell crank pivoted on the slide and having a roller adapted to coact with the interior or exterior of the cup and pass through the notch, a separable terminal connected with the slide, and an operating member having a yielding connection with the bell crank.

10. The combination, with a controller barrel, of a notched member connected therewith, a slide, a lever pivoted on the slide, a roller on the lever adapted to coact with the notched member, separable terminals connected with the slide, an operating rod, a spring interposed between it and the slide whereby the rod yieldingly operates the slide, and a yielding connection between the rod and said lever.

11. The combination, with a controller, of a safety device connected therewith comprising a folding platform, means for preventing effective actuation of the controller, and connecting mechanism between the same and said platform, said connecting mechanism including a yielding connection enabling the platform to move to final position after the stopping of the connecting mechanism at the controller.

12. The combination, with a controller barrel, of separable terminals in the circuit to the controller, mechanism for separating such terminals, mechanism under the control of the controller barrel for preventing the return of such terminals, a movable support, and a connection between the same and the separating mechanism mentioned.

13. The combination, with a controller, of a separable terminal in the circuit thereof, a movable platform, a spring tending to raise the platform, connecting mechanism between the platform and one of said terminals tending to separate the terminals when the platform is raised, said connecting

130

mechanism having yielding parts enabling the platform to move into final position after the terminals are brought into contact.

14. The combination, with a controller, of a movable safety member, separable terminals for controlling the circuit of the controller, means for separating such terminals when the safety member is moved in one direction, means enabling the safety member to move in both directions when the controller is at the "off" position but preventing it moving in the closing direction when the controller is at an "on" position, a movable platform, and a connection between it and the safety member.

15. The combination, with a controller, of a member movable thereby having an opening, a safety device adapted to pass through such opening in either direction, said device being also adapted to pass across the member in one direction only, and separable terminals opened by the last mentioned direction of movement, a movable platform, and a connection between it and the safety device.

16. The combination, with a controller barrel, of a member movable therewith and having a wall with a notch in it, a blocking device adapted to move across the member independently of the notch in one direction but not in the opposite direction, a pair of separable terminals, means whereby the movement of the blocking device in the direction it can move across said member separates the terminals, a movable platform, means tending to raise it, and a connection between the platform and the blocking device adapted to give the blocking device the last mentioned movement when the platform is freed from depressing weight.

17. The combination, with a controller barrel, of a cap rotatable therewith and having a notch in its wall, a device adapted to stand on either the outer or inner side of the wall and adapted also to pass through said notch in either direction, a movable member carrying said device, a slide carrying said member, whereby the device may pass over the edge of the wall from one side to the other but not in the reverse direction, and separable terminals controlled by the movement of said device.

18. The combination, with a controller, of coacting terminals, one of which is movable for controlling the circuit of the controller, means for moving one of said terminals away from the other whether the controller be at "on" or "off" position,

means for blocking the return of such moved terminal when the controller is at "on" position, a movable platform, connecting mechanism between it and the movable terminal, and a take-up spring in said connecting mechanism.

19. The combination of a controller barrel, a wall rotatable therewith and having a notch through it, a slide, a bell crank carried by said slide, a roller carried by the bell crank adapted to ride on either side of the wall and pass through the notch and also pass over the edge of the wall, a pair of separable terminals, one of which is connected with said slide, and means for moving the bell crank and slide.

20. The combination, with a controller barrel, of a cup rotatable therewith and having a notch through its wall, a member adapted to stand either on the outside or inside of the cup and adapted to pass through said notch and adapted also to pass over the wall of the cup in one direction, a pair of separable terminals, one of which is connected with said member, and means for moving the member from one side of the cup wall to the other over the edge of the wall.

21. The combination, with a controller, of separable terminals for controlling the circuit thereof, means movable by the controller for preventing the return of such terminals when separated unless the controller be at "off" position, means independent of the controller for returning the terminals into coaction when the controller allows it, and a take-up spring included in the last mentioned means adapted to be constrained when the controller does not allow the return of such separable terminals.

22. The combination, with a controller, of separable terminals for controlling the circuit thereof, means movable by the controller for preventing the return of such terminals when separated unless the controller be at "off" position, a platform, means tending to raise it, connective mechanism between said platform and one of the terminals adapted to return said terminal into active position when the controller allows it, and a take-up spring in such connecting mechanism.

In testimony whereof, I hereunto affix my signature in the presence of two witnesses.

CLYDE E. COCHRAN.
